UNITED STATES PATENT OFFICE.

ROBERT ALDEEN NELSON, OF OAKLAND, CALIFORNIA.

TRAMMEL.

1,219,141.

Specification of Letters Patent. Patented Mar. 13, 1917.

Application filed July 15, 1916. Serial No. 109,446.

To all whom it may concern:

Be it known that I, ROBERT A. NELSON, a citizen of the United States, and a resident of Oakland, in the county of Alameda 5 and State of California, have invented a new and Improved Trammel, of which the following is a full, clear, and exact description.

My invention relates to a trammel or beam compass. Objects of the invention are to provide a novel means for adjusting the trammel point and for holding it securely in the adjusted position; to provide improved clamping means to secure the device 15 to a beam; and to provide a novel caliper attachment that may be readily applied to the trammel points.

The invention will be particularly explained in the specific description following.

Reference is to be had to the accompanying drawings forming a part of this specification in which similar reference characters indicate corresponding parts in all the views.

Figure 1 is a side elevation of a beam compass, embodying my invention, one of the trammels being in vertical section;

Fig. 2 is a transverse vertical section on the line 2—2, Fig. 1;

Fig. 3 is a similar section on the line 3—3, Fig. 1.

Since both the trammels are alike, it will suffice to refer particularly to one.

The body 10 of the trammel has an oblong opening, as usual, to receive the beam 11. A set screw 12 serves to clamp the trammel to the beam, and in order that the set screw may not mar the beam, a wear plate or follower 13 is provided above the beam, said plate having at the upper side guide studs 13^a extending through vertical pin-holes 10^a in the body 10.

In order to adjust the trammel point 16 and house the adjusting means, as well as to provide for securely fastening the point in adjusted position and enable the adjustments to be effected with facility and dispatch, the following means is employed: At the lower end of the body 10, a horizontally disposed box-like extension 14 is formed, one end being open. In the said extension, a block 15 is slidably fitted and to said block, at the under side, the trammel 16 is secured so as to move with the block. 55 A longitudinal slot 17 in the under side of the extension 14 and communicating with

the interior thereof, permits of the sliding movement of the trammel point in response to the movement of the block 15. The block 15 is moved longitudinally by a horizontal screw 18, taking into the threaded bore of said block. The screw is clamped to the vertical end wall of the extension 14 by a collar 19, the arrangement being such that by a turning of the knurled head of the screw 18, the block will be moved forward or back in the extension 14, and thereby carry the trammel point 16 backward or forward longitudinally of the slot 17.

To detachably connect the trammel point 70 with the block 15, the upper end of the point is reduced and threaded as at 20, thereby producing a shoulder at the said reduced portion, the threaded terminal taking into an internally threaded hole in the under 75 side of the block 15.

A threaded stem section 21 is produced below the terminal end 20 of the trammel point and receives a nut 22 for binding the trammel point in position, a washer 23 being preferably provided between the nut 22 and the under side of the extension 14 at the slot 17.

In practice it will be clear that the loosening of the nut 22 will permit the block 15 to be moved by the screw 18 to adjust the position of the trammel point, and the tightening up of the nut 22 will then serve to firmly hold the point in the adjusted position. The arrangement provides a neat 85 construction and houses the adjusting block and screw, leaving only the set nut 22 below the extension 14.

To convert the trammel or compass into calipers, an attachment 24 is provided and formed with a tubular shank tapering at the lower end to fit over the trammel point 16, said shank being secured to the trammel point by a set screw 25 and having its lower end 26 turned laterally.

Having thus described my invention, I claim as new and desire to secure by Letters Patent:

1. A trammel including a body having a transverse opening to receive a beam and formed with a box-like extension at the lower end below said opening, one end of said extension being open, and there being a longitudinal slot in the bottom of said extension communicating with the interior thereof, a block slideable longitudinally in said extension and having a threaded bore,

a screw swiveled to the wall of the said extension opposite the open end and provided with a head at the exterior of said wall, said screw engaging the threaded bore of 5 the block, a trammel point extending at its upper end through the longitudinal slot of said extension and detachably secured to the under side of the said block, said point having a threaded section adjacent to the upper 10 end extending through the said slot, a nut on said threaded section, and a washer between said nut and the under side of the extension.

2. A trammel including a body formed 15 with a transverse opening to receive a beam, said body having a horizontally disposed box extension, integral with said body below the said opening, a block housed within said box extension and slidably longitudinally therein, a screw engaging said block 20

to move the said block back and forth in said extension, the bottom of said extension being slotted, a trammel point extending at its upper end through said slot and secured to said block to slide with the latter, and a 25 clamp nut threaded onto the said point at the under side of said extension.

3. A trammel having a body formed with a transverse opening to receive a beam, a trammel point in said body at the lower end, 30 a set screw in said body and extending into the opening at the top thereof, a clamp plate in the opening of the body to bear against the beam, and guide pins on said clamp plate extending through members on 35 the body, the said pins having heads above the said body members to limit the downward movement of the clamp plate and prevent displacement of the latter.

ROBERT ALDEEN NELSON.
